GLOVE

Marinette Blanc, Hewlett, N. Y., assignor to Picardy Mills, Inc., Brooklyn, N. Y., a corporation of New York

Application April 28, 1949, Serial No. 2,325

Term of patent 3½ years

(Cl. D3—11)

To all whom it may concern:

Be it known that I, Marinette Blanc, a citizen of the United States, residing at Woodmere, city of Hewlett, Long Island, in the county of Nassau and State of New York, have invented a new, original, and ornamental Design for a Glove, of which the following is a specification, reference being had to the accompanying drawings, forming part thereof, wherein

Fig. 1 is a rear view of a glove showing my new design,

Fig. 2 is a side view thereof,

Fig. 3 is a front view, and

Fig. 4 is a rear view thereof, as it appears in buttoned position.

I claim:

The ornamental design for a glove, substantially as shown and described.

MARINETTE BLANC.
